US00D741681S

(12) **United States Design Patent**
Kirby et al.

(10) Patent No.: US D741,681 S
(45) Date of Patent: ** Oct. 27, 2015

(54) **HAND TOOL**

1,024,388	A	4/1912	Bartlett
1,450,674	A	4/1923	Marston
1,770,920	A	7/1930	Hermani
1,859,772	A	5/1932	Hiering
1,907,107	A	5/1933	Hiering

(71) Applicant: **Milwaukee Electric Tool Corporation**,
Brookfield, WI (US)

(72) Inventors: **Michael Kirby**, Menomonee Falls, WI (US); **Marc S. D'Antuono**, Wauwatosa, WI (US); **Matthew M. Kuester**, Manitowoc, WI (US); **Joseph H. Ellice**, Greenfield, WI (US); **Scott D. Bublitz**, Hartland, WI (US)

DESCRIPTION

FIG. 1 is a front perspective view of a hand tool.
FIG. 2 is a rear cross-sectional view of the hand tool taken generally along section line 2-2 in FIG. 1.
FIG. 3 is a cross-sectional view of the hand tool of FIG. 2 with a bit drive guide removed; and,
FIG. 4 is a rear perspective view of the hand tool of FIG. 1, illustrated in an open position.
Portions of the hand tool shown in broken lines are included for the purpose of depicting unclaimed portions of the hand tool that form no part of the claimed design.

1 Claim, 3 Drawing Sheets
